GAS AND LIQUID MIXER

Charles Dalrymple Macgill, Glasgow W. 3, Scotland, assignor to Barr & Stroud, Limited, Glasgow, Scotland

Application August 6, 1942, Serial No. 453,895
In Great Britain July 21, 1939

4 Claims. (Cl. 299—86)

This invention refers to a method of and apparatus for adding quantities of liquid to systems in which gas under pressure is flowing, the invention being more particularly concerned with air pressure systems for cleaning the windows of rangefinders and like optical instruments by directing air under pressure on to the glass, to clear away rain, spray, soot, or the like.

In this connection, it has been found that where a deposit has formed on the window, e. g. a deposit of salt, or an oily deposit from funnel smoke on board ship, the use of a solvent liquid with the air may be necessary for cleaning purposes, and the principal object of the invention is to provide for the addition of charges of solvent liquid, for example, water itself, or a solution of a chemical in water, to the air.

According to this invention, quantities of liquid are added to a system in which gas under pressure is flowing by connecting a container for liquid, at a position below the liquid level in the container, to the pressure system, with valve control of the connection, so that, connecting the container to the system opens the valve, gas under pressure passes into and up through the liquid in the container, builds up a pressure above the liquid in the container and forces liquid out of the container into the pressure system by way of the connection and past the gas flowing into the container through the connection, with the result that the liquid is carried away by the flowing gas in the system in quantities depending upon the amount and duration of opening of the valve.

For cleaning the window of a rangefinder or like optical instrument, there is provided in accordance with this invention a system comprising piping or tubing forming an air line for conveying air under pressure for discharge on to the window (or windows) of the rangefinder through a nozzle (or nozzles) beside the window, a connection piece in the air line with a branch passage in the connection piece, a liquid container device with a passage communicating with the interior of the container at a position below the liquid level therein, the container passage being connected to the branch passage of the connection piece, and a valve interposed between the air line and the container, the said passages when the valve is open serving both for inlet of air to the container (where it rises up through the liquid and creates a pressure above it), and for outlet of liquid from the container past the entering air and into the air line, to be carried away and

discharged as a spray on to the window with the air.

The container device is readily attachable to and removable from the connection piece, and the branch passage of the connection piece has a valve in it which serves to close the branch passage when the container device is not applied, and the passage of the container device also has a valve in it which normally closes the passage from the container.

When the container device is removed from the connection piece, the branch passage of the connection piece is closed by a valve which is opened by the action of applying the container device and closes of itself when the container device is removed.

The invention, as applied to a rangefinder window cleaning system will now be described with reference to the accompanying drawing, in which:

Figure 1 shows, more or less diagrammatically, a rangefinder equipped with a compressed air window cleaning system, and

Figure 2 is a side sectional view showing the container device for introducing liquid into the air system.

Figure 3 is a detail, fragmentary, view, partly in vertical section and partly in elevation showing the valve in the branch passage in an open position, resulting from application of the container device to the connection piece.

Figure 1 shows rangefinder A, air pump B, and liquid container device C.

The pump B delivers air under pressure by way of a main delivery tube 1, a connection piece D, and tubes 2 to each of the windows 3 of the rangefinder, on to which the air is directed from a nozzle 4 at the end of each of the tubes 2.

The connection piece D is shown in detail in Figures 2 and 3 and comprises a central limb 5, a cross-part 5a constituting two branch connections 6 for the tubes 2, an air inlet connection 7, and a branch passage 8 controlled by an outwardly closing ball valve 9 having a seat 9a and spring 10. An enlarged portion in the upper end of the branch passage 8 forms a chamber 11a and an inner tube 11 extends from the said chamber 11a into the cross-part 5a of the connection piece D.

When the window cleaning system is functioning without the container device being fitted in place, the branch passage 8 is closed by the ball valve 9 and air from the pump B passes into the connection piece D and is distributed to the

tubes by way of the connections 6, and thence to the windows 3.

The container device C comprises a cylindrical container 12 with a neck 13 through which an air inlet and liquid outlet port 19 extends, and a valve 14 controlling the port 19. At the side of the container 12 there is a sight tube 15 and at the opposite end from the neck 13 there is a filling opening 16 with a screw closure cap. The valve 14 is a cylindrical slide valve with a groove 14a around the valve body, and having an operating head 14b, and a spring 18 acting on the valve body to keep the valve closed.

For use, the container device C is applied to the connection piece D as shown in Figure 2 and secured by a union nut 17 so that the branch passage 8 of the connection piece communicates with the port 19, the neck 13 depressing the ball valve 9. On then opening the valve 14 by pushing the operating head to the left against the action of the spring 18, into the open position, the interior of the container 12 is put into communication with the interior of the connection piece D by way of port 19 and groove 14a. Assuming the container 12 to be charged with liquid, air under pressure passes up the inner tube 11 and rises to the surface of the liquid where it builds up a pressure so that liquid is forced down through port 19 and groove 14a past the valve 9 through tube 11 into the air line and is ejected with the air in the form of a fine spray against the windows 3.

On releasing the valve head, the valve 14 closes and cuts off the liquid supply so that dry air is delivered to the windows, after the liquid already in the system has been ejected.

The container 12 must in use be closed to atmospheric pressure.

To avoid undue consumption of the solvent liquid, the following procedure may be adopted. The operator starts the motor of the pump B and presses the head of the valve 14 for two or three seconds so as to build up a pressure in the interior of the container 12. He then releases the valve and stops the pump motor. Next he presses the valve head again, noting a limited fall in the liquid level as shown by the sight tube 15. Thereafter he releases the valve head and re-starts the motor, as a result of which the charge of liquid which has entered the air system is discharged on to the windows through the nozzles 4. This charge will usually be sufficient to remove a deposit from the windows.

After the introduction of a charge of liquid into the air system the container 12 may be removed from the connection piece D in which case the valve 9 automatically closes. If more than one rangefinder is fitted with a window cleaning system of this kind, the container may be transferred from one system to another, as required.

I claim:

1. In apparatus for selectively delivering air or air and liquid under pressure, the combination of a source of supply of air under pressure, a connection piece of substantially T-form having a passage in its central limb communicating with a passage in its cross-part, and a valve chamber in the passage of said central limb remote from the point of connection of said passages, piping for conveying the air under pressure to the passage of said central limb, piping connected to each outlet of the cross-part of said connection piece, provided with a nozzle, an inner tube in the passage of said central limb having its one end communicating only with said valve cham-

ber and its other end communicating with the passage of said cross-part, and disposed so as to leave an annular space around the inner tube separated from the valve chamber, whereby said air under pressure is required to pass through said annular space in a direction away from said valve chamber and then into and through said inner tube to the valve chamber, an outwardly closing valve in said valve chamber, a liquid container removably fitted to said connection piece at the end of said central limb adjacent said valve and adapted to unseat said valve when the liquid container is connected to said connection piece, said liquid container provided with a port communicating with said valve chamber beyond said valve and with the container interior at a position below the liquid level therein, and a valve in said port for controlling inlet of air to and exit of liquid from said container.

2. In apparatus for selectively delivering air or air and liquid under pressure, the combination of a source of air under pressure, a spray nozzle, and piping forming an air line for conveying air under pressure to said spray nozzle, said air line including a connection piece provided with a branch passage, a liquid container removably fitted to the connection piece with a passage in the container communicating with its interior at a position below the liquid level in the container and connected to the said branch passage, a valve in the branch passage to close that passage when the container is not applied, and a valve in the passage of the container to close the container when removed from the connection piece, the said connected passages when the valves are open serving both for inlet of air to the container and for outlet of liquid from the container past the entering air and into the air line to be carried away and discharged as a spray in quantities depending on the amount and duration of opening of the valves.

3. In apparatus for selectively delivering air or air and liquid under pressure, the combination of a source of air under pressure, a spray nozzle, and piping forming an air line for conveying air under pressure to said spray nozzle, said air line including a connection piece provided with a branch passage, a liquid container removably fitted to the connection piece with a passage in the container communicating with its interior at a position below the liquid level in the container and connected to the said branch passage, a valve in the branch passage which is opened by the action of applying the container to the connection piece and which closes of itself when the container is removed, and a valve in the passage of the container to close the container when removed from the connection piece, the said connected passages when the valve of the container is open serving both for inlet of air to the container and for outlet of liquid from the container past the entering air and into the air line to be carried away and discharged as a spray in quantities depending on the amount and duration of opening of the valve in the passage of the container.

4. In apparatus for selectively delivering air or air and liquid under pressure, the combination of a source of air under pressure, a spray nozzle, and piping forming an air line for conveying air under pressure to said spray nozzle, said air line including a connection piece provided with a branch passage, a liquid container removably fitted to the connection piece with a passage in the container communicating with its

interior at a position below the liquid level in the container and connected to the said branch passage, a valve in the branch passage which is opened by the action of applying the container to the connection piece and closes of itself when the container is removed; and a valve in the passage of the container which is opened by hand and self-closing when released to close the container when removed from the connection piece,

the said connected passages when the valve of the container is open serving both for inlet of air to the container and for outlet of liquid from the container past the entering air and into the air line to be carried away and discharged as a spray in quantities depending on the amount and duration of opening of the valve in the passage of the container.

CHAS D MACGILL.
